UNITED STATES PATENT OFFICE.

ADAM NICKEL, OF NEW YORK, N. Y., ASSIGNOR TO WESSELL, NICKEL & GROSS,
OF NEW YORK, N. Y.

REPEATING-ACTION FOR GRAND PIANOS.

No. 879,978.

Specification of Letters Patent.

Patented Feb. 25, 1908.

Application filed December 26, 1907 Serial No. 408,101.

To all whom it may concern:

Be it known that I, ADAM NICKEL, a citizen of the United States, residing at New York city, Manhattan, county and State of New York, have invented new and useful Improvements in Repeating-Actions for Grand Pianos, of which the following is a specification.

This invention relates to a repeating action for grand pianos which responds delicately to the touch and permits the hammer to fall away freely from the swing while the key remains depressed.

In the accompanying drawing: Figure 1 is a side elevation, partly in section, of my improved grand piano action, showing the normal position of the parts, and Figs. 2 and 3 are similar views showing consecutive positions of the jack and adjoining parts immediately before and after the hammer has struck the string.

The support 10 fulcrumed at 11 is operated by key 12 through capstan 13, as usual. To the forward part of support 10 is pivoted at 14 an elbow-shaped jack 15 having a lower forwardly projecting toe 16. Back of fulcrum 14 there is secured to support 10 by pin 17 a spring 18 that exerts a pressure against toe 16 by means of an interposed arm 19 pivoted to support 10 at 20. The tension of spring 18 may be adjusted by a regulating screw 21 tapped into support 10 and engaging a heel 22 of the spring. Spring-arm 19 is padded below toe 16 as at 23. Into arm 19 is tapped a screw 24 forming a projection, the head 25 of which extends slightly above toe 16 and is adapted to be operatively engaged by a padded escapement-button 26 carried by regulating rail 27. To accommodate screw 24, toe 16 may be perforated as at 28, Fig. 2. Near its upper end there is pivoted to jack 15 at 29, the lower end of a link 30, the upper end of which is pivoted at 31 to a lever 32 fulcrumed to support 10 at 33. Lever 32 is cushioned as at 34 to sustain knuckle 35 of hammer 36, as usual. Normally there is formed between front of jack 15 and link 30, an obtuse reentrant angle which is defined by a regulating button 37 tapped into jack 15 and engaging an abutment 38 of support 10.

In the normal position of the parts, spring arm 19 tilts jack 15 backwards, so that button 37 is pressed against shoulder 38, (Fig. 1).

Upon the depression of the key, support 10 is swung on fulcrum 11 to advance the hammer towards string 39. When the hammer is within a short distance of the string, screw 24 will engage button 26, the latter thus causing spring-arm 19 to swing away from toe 16, so that thereby jack 15 becomes entirely relieved of spring pressure, (Fig. 2). Toe 16 will next strike button 26, so that the top of jack 15 is tilted forward until fulcrum 29 is advanced slightly beyond a line drawn through fulcrums 31 and 14, (full lines Fig. 3). After the hammer has struck the string, it is free to fall back therefrom while the key remains depressed, because it will, by its own weight, through lever 32 further tilt jack 15 and link 30 forward. This tilting movement is limited by the engagement of toe 16 with pad 23 and may be readily accomplished, because during this movement the jack is entirely uninfluenced by spring 18. If the key is now partly released, the spring which again operatively engages the jack, will throw the latter back into its normal position, so that a delicate repeating action is insured. Upon the entire release of the key, all the parts are returned to the position shown in Fig. 1.

I claim:

1. A repeating action for grand pianos provided with a jack, a spring operatively engaging the same and adapted to throw the jack backwards, means for releasing the jack from the spring, a lever linked to the jack, and a hammer supported by the lever, substantially as described.

2. A repeating action for grand pianos provided with an elbow-shaped jack, a spring operatively engaging the toe thereof, means for releasing the toe from the spring, a lever linked to the jack, and a hammer supported by the lever, substantially as specified.

3. A repeating action for grand pianos provided with a support, an elbow-shaped jack pivoted thereto, a spring mounted on the support and adapted to operatively engage the jack, an escapement successively engaging the spring and jack, a lever linked to the jack, and a hammer supported by the lever, substantially as specified.

4. A repeating action for grand pianos provided with a support, an elbow-shaped jack pivoted thereto, a spring-arm engaging the jack, a projection extending upwardly from the arm, an escapement successively engag-

ing the projection and jack, a lever linked to the jack, and a hammer supported by the lever, substantially as specified.

5. A repeating action for grand pianos provided with a support, an elbow-shaped jack pivoted thereto, an arm also pivoted to the support and engaging the jack, a spring engaging the arm, a projection extending upwardly from the arm, an escapement suc-

sively engaging the projection and jack, a lever linked to the jack, and a hammer supported by the lever, substantially as specified.

Signed by me at New York city, (Manhattan,) N. Y., this 23rd day of December, 1907.

ADAM NICKEI.
